FOREIGN PATENT DOCUMENTS

RU 106418 U1 7/2011

Primary Examiner — Austin Murphy

(74) Attorney, Agent, or Firm — Harrity & Harrity, LLP

CLAIM

The ornamental design for a multiple head transaction device, as shown and described.

DESCRIPTION

FIGURE is a perspective view of a multiple head transaction device showing our new design.

The broken lines shown in the drawing are for illustrative purposes only and form no part of the claimed design. The shade lines in the FIGURE show contour and not surface ornamentation.

1 Claim, 1 Drawing Sheet

See application file for complete search history.
